(57) **CLAIM**

The ornamental design of a fifth wheel head support assembly, shown and described.

DESCRIPTION

FIG. 1 is a perspective view of the fifth wheel head support assembly of the present invention;

FIG. 2 is a rear elevational view, the front elevational view being a substantial mirror image thereof;

FIG. 3 is a left side elevational view, the right side elevational view being a substantial mirror image thereof; and, FIG. 4 is a top plan view thereof.

The broken line showing of environment is for illustrative purposes only and forms no part of the claimed design.
